[57] CLAIM

The ornamental design for a display carton, as shown and described.

DESCRIPTION

FIG. 1 is a perspective of a display carton embodying my new design;

FIG. 2 is a top plan view thereof;

FIG. 3 is an end elevational view, the opposite ends of the carton being the same;

FIG. 4 is a bottom plan view thereof;

FIG. 5 is a side elevational view, the opposite sides of the carton being the same;

FIG. 6 is a plan view of the carton in knocked-down, flat-folded condition.

FIG. 1

FIG. 3

FIG. 2
